CIRCUITS FOR PASSING OR STOPPING A FREQUENCY BAND OF ALTERNATING CURRENTS.

Application filed November 30, 1920. Serial No. 427,892.

It is an object of my invention to provide a network that shall have predetermined characteristics as to its circuit functions between two defined limits of frequency of the current traversing it. The term circuit functions includes the well known functions of impedance, admittance, resistance, conductance, reactance and susceptance.

Another object of my invention is to provide a new and improved system of circuits that shall effectively pass (or stop) currents of frequency between certain limits, but stop (or pass) currents outside those limits. Another object of my invention is to provide a system of circuits that shall offer a high (or low) impedance to currents of a certain frequency range, but low (or high) impedance to currents of frequencies outside that range. Such circuits find useful applications in many situations; for example, in multiplex telephone work where, in some cases, it is desired to admit to certain apparatus only currents within a certain frequency range, and, in other cases, effectively to bar out from the apparatus currents within a certain frequency range.

Referring to the drawings, Figure 1 is a diagram illustrating a system of circuits for offering low impedance to a frequency band and relatively high impedance to frequencies outside that band; Fig. 2 is a diagram illustrating a system designed to bar currents within a certain frequency band while passing currents of frequencies outside that band; Figs. 3, 4 and 5 are characteristic diagrams for the apparatus illustrated in Figs. 1 and 2; Fig. 6 is a diagram of a modification, a band reactance neutralizer of one loop; Fig. 7 is a characteristic diagram for the apparatus of Fig. 6; Fig. 8 is a diagram of a band reactance neutralizer of three loops; Fig. 9 is a corresponding characteristic diagram; and Fig. 10 is a frequency scale to which reference will be made in explaining a certain notation employed.

In Fig. 1 the numeral 11 indicates a source

of alternating current of varying frequency or of different frequencies superposed, and 12 represents apparatus connected in circuit therewith to which it is desired to admit only those currents having their frequency between certain limiting values. Between 11 and 12 are a plurality of parallel circuits, each comprising an inductance L, a condenser C, and a resistance R in series. These letters, L, C and R, are also used in the following discussion to indicate the numerical measures of the inductance, capacity, and resistance of the three elements respectively. These values are not the same for the different parallel branches, but they may differ in gradation from one branch to the next, for example in the manner that will be pointed out in the explanation that follows. In a special case that will be considered by way of illustration, it will be shown that with twelve parallel branches the impedance varies with the frequency somewhat according to the curve 1 in Fig. 3, though it should be mentioned that the abscissæ in Fig. 3 do not represent frequency, but a function of frequency, as will be fully explained presently.

Of course each branch L—C—R of Fig. 1 is resonant to a particular frequency f_0 such that

$$f_0 = \frac{1}{2\pi} \sqrt{\frac{1}{LC}}$$

The design is such that the values of f_0 for the different branches differ in a regular gradation. Thus the system comprises a series of resonant branch conductors having their resonant frequencies distributed over a frequency band which is accordingly a band of low impedance.

In considering the behavior of resonant circuits or branches, in which the effect of the leakage conductance of the condenser may be neglected, it is usual to express the impedance z , resistance r , reactance x , ad-

mittance y , conductance g , and susceptance b as functions of the resistance R , inductance L , capacity C , and frequency f (where $\omega = 2\pi f$.) Thus we have

$$5 \quad \text{Impedance, } z = \sqrt{R^2 + \left(L\omega - \frac{1}{C\omega}\right)^2}$$

$$\text{Resistance, } r = R$$

$$10 \quad \text{Reactance, } x = L\omega - \frac{1}{C\omega}$$

$$15 \quad \text{Admittance, } y = \frac{1}{R^2 + \left(L\omega - \frac{1}{C\omega}\right)^2}$$

$$\text{Conductance, } g = \frac{R}{R^2 + \left(L\omega - \frac{1}{C\omega}\right)^2}$$

$$20 \quad \text{Susceptance, } b = \frac{\left(L\omega - \frac{1}{C\omega}\right)}{R^2 + \left(L\omega - \frac{1}{C\omega}\right)^2}$$

25 The above formula for conductance may be established as follows: Let dashes be placed over the letters to indicate corresponding vector values. Then in the conventional complex number notation,

$$30 \quad \bar{z} = R + ix$$

and

$$\bar{y} = \frac{1}{\bar{z}} = \frac{1}{R + ix} = \frac{R - ix}{R^2 + x^2} = \frac{R}{R^2 + x^2} + i \frac{-x}{R^2 + x^2}$$

35 The real term

$$\frac{R}{R^2 + x^2}$$

40 is the conductance, and substituting for x its value as given above, the formula given for conductance g is obtained at once.

When working with circuits or branches connected in series, the resistance, reactance, and impedance are used, but when working with circuits connected in parallel the conductance, susceptance, and admittance are used. In analytical work the frequency f is in some ways an inconvenient variable, and especially for purposes of graphical representation of the solution of branching networks. I find that a more convenient way of dealing with these problems involving resonant circuits consists in expressing z , x , y , g , and b as functions of the resistance R , selectance S , and a new variable α , which I shall call the "frequency function". Thus

$$60 \quad z = R\sqrt{1 + \alpha^2 S^2}$$

$$r = R$$

$$x = \alpha_0 R S$$

$$65 \quad y = \frac{1}{R} \frac{1}{\sqrt{1 + \alpha^2 S^2}}$$

$$g = \frac{1}{R} \frac{1}{1 + \alpha_0^2 S^2}$$

$$b = \frac{1}{R} \frac{-\alpha_0 S}{1 + \alpha_0^2 S^2}$$

70

where

$$S = \sqrt{\frac{L}{C R^2}} \text{ and } \alpha_0 = \frac{\omega^2 - \omega_0^2}{\omega \omega_0} = \frac{f^2 - f_0^2}{f f_0}$$

in which f_0 is the frequency to which the 75 particular resonant circuit is attuned.

The foregoing expressions in terms of the frequency function α and the selectance S may be established readily by substitution in the formulas already given in terms of R , L and C . Thus, for example, we may prove the first of the foregoing list of formulas, viz,

$$z = R\sqrt{1 + \alpha_0^2 S^2}.$$

85

In this expression substitute

$$\frac{\omega^2 - \omega_0^2}{\omega \omega_0}$$

90

for α_0 and substitute

$$\sqrt{\frac{L}{C R^2}}$$

95

for S . Since these steps involve simple algebra, they will be omitted here, but the result will be the formula written out heretofore for z in terms of R , L and C . Since all the steps are reversible, this proves the formula for z in terms of α_0 and S . Similarly, the other formulas in terms of α_0 and S may be proved.

100

Though the function α_0 deduced and defined as above is the function of some particular circuit, it need not be so restricted and may be used as a new variable in place of ω or f whether or not there be any circuit involved which is actually attuned to frequency f , and it is in this more general aspect, and as such a new variable, that I have used this function in the present solution of the problem of the system of low impedance circuits for a given frequency band in Fig. 1.

110

This solution is quite general, except that it requires one-half of the width of the frequency band to be small compared to the medial frequency of the band, a condition to which practically all examples met with in practice may readily be made to conform. In the notation that follows, where n is the number of the parallel branch circuits, the condition just referred to can be stated by saying that—

$$\frac{f_{\frac{n-1}{2}} - f_{\frac{1-n}{2}}}{2f_0}$$

125

is small compared to unity.

130

In explanation of the notation employed in the foregoing formula, reference is made to Fig. 10, a uniform frequency scale extending from P to Q with zero indicated at the left. Let this range from P to Q be divided into twelve equal parts, where 12 is a particular value of the general number n . We wish to designate the frequencies at the respective midpoints of the twelve intervals. Call the frequency f_0 at the midpoint of the range PQ, and since the midpoint of the first interval to the right is a half interval distant, call it $f_{\frac{1}{2}}$. Going on, consistently with the foregoing the frequency at the midpoint of the second interval to the right from f_0 will be $f_{\frac{3}{2}}$, and so on. The frequency at the midpoint of the last interval will be $f_{\frac{11}{2}}$, or, more generally,

20

$$f_{\frac{n-1}{2}}$$

At the left of the main midfrequency f_0 , consistently with the foregoing, we shall have interval midpoint frequencies

$$f_{-\frac{1}{2}}, f_{-\frac{3}{2}}, \dots, f_{-\frac{11}{2}},$$

30 or, more generally, for this last value,

$$f_{\frac{1-n}{2}}$$

From the foregoing it will be seen that the interval midfrequency values, such as

$$f_1, f_{\frac{3}{2}}, \dots, f_{\frac{11}{2}}, f_{\frac{13}{2}}, \dots$$

may be represented generally by the formula

40

$$f_{\frac{n-m}{2}}$$

where m takes the odd number values from $-(2m-1)$ to $+(2m-1)$.

45 This system of notation can be employed for other functions than frequency. For example, if the midfrequency of a certain interval is

50

$$f_{\frac{n-m}{2}}$$

and if a branch circuit corresponding thereto has a coil and condenser of appropriate

values, their respective inductance and capacity may be designated

55

$$L_{\frac{n-m}{2}}$$

and

$$C_{\frac{n-m}{2}}$$

60

In the particular case when $n=12$, as assumed for Fig 10, and when we have regard to the extreme right-hand interval of the range, viz, the twelfth interval, then these expressions become

$$L_{\frac{1}{2}} \text{ and } C_{\frac{1}{2}}$$

In describing the system of Fig. 1, I shall define its construction in terms only of the 70 resistances, selectances, and frequency functions of the parallel branches represented respectively by r , s , and α .

Two of the more important forms of the system shown in Fig. 1 are: first, one in 75 which the impedance is small and substantially constant throughout the band; and second, one in which the rate of change of the reactances is negative and substantially constant throughout the band. Of these two forms the former is of more immediate utility, and will be described in some detail by way of an example for all cases.

In the form of the apparatus of Fig. 1 chosen for illustration, there are n parallel branches, all having substantially equal resistances and selectances, but with their frequency functions α varying from branch to branch in arithmetical progression, with common difference Δ . I impose on the selectance S , the condition that it shall be not greater than the reciprocal of Δ that is

$$S \leq \frac{1}{\Delta}$$

95

As the frequency of each branch is determined by the expression

$$\frac{f_{\frac{n-m}{2}}^2 - f_0^2}{f_0 f_{\frac{n-m}{2}}} = \frac{n-m}{2} \Delta$$

100

therefore

$$f_{\frac{n-m}{2}} = \left[\frac{n-m}{4} \Delta + \left\{ 1 + \frac{1}{8} \left(\frac{n-m}{2} \Delta \right)^2 - \frac{1}{128} \left(\frac{n-m}{2} \Delta \right)^4 + \frac{3}{3072} \left(\frac{n-m}{2} \Delta \right)^6 - \dots \right\} \right] f_0$$

When $\frac{n-m}{2} \Delta$ is small compared to unity as 105 always is in any practical case,

$$f_{\frac{n-m}{2}} = \left(1 + \frac{n-m}{4} \Delta \right) f_0$$

Let $S = \frac{p}{\Delta}$ where $0 < p \leq 1$, and we get

$$\sqrt{\frac{L_{\frac{n-m}{2}}}{C_{\frac{n-m}{2}} R^2}} = \frac{p}{\Delta} \text{ and } \sqrt{L_{\frac{n-m}{2}} C_{\frac{n-m}{2}}} = \frac{1}{2\pi \left(1 + \frac{n-m}{2}\Delta\right) f_0}$$

$$L_{\frac{n-m}{2}} = \frac{pR}{2\pi\Delta \left(1 + \frac{n-m}{2}\Delta\right) f_0} \text{ and } C_{\frac{n-m}{2}} = \frac{\Delta}{2\pi pR \left(1 + \frac{n-m}{2}\Delta\right) f_0 pR}$$

Thus in the case of the 12-branch filter,

$$L_{\frac{n-m}{2}} = \frac{pR}{2\pi\Delta \left(1 + \frac{11}{2}\Delta\right) f_0} \text{ and } C_{\frac{n-m}{2}} = \frac{\Delta}{2\pi pR \left(1 + \frac{11}{2}\Delta\right) f_0}$$

We may now consider a numerical example.

Let $f_0 = 10^6$, $\Delta = 10^{-2}$, $p = 1$, $R = 10^{-1}$; then $L_{\frac{n-m}{2}} = 0.015085$ millihenrys, $C_{\frac{n-m}{2}} = 0.15085$ microfarads, . . . $L_{\frac{n-m}{2}} = 0.016843$ millihenrys, $C_{\frac{n-m}{2}} = 0.16843$ microfarads, $f_{\frac{n-m}{2}} = 1.0275 \times 10^5$, . . . $f_{\frac{n-m}{2}} = 0.9725 \times 10^5$, $S = 100$, $R = 0.1$ ohm.

The apparent impedance of the filter for currents having frequencies within the assigned frequency band is 0.034 ohms.

Fig. 3 is a set of characteristic curves for the system of Fig. 1 as developed according to the preceding theory of design. The curve 1 of Fig. 3 represents the impedance for a filter having twelve branches, in which $\Delta S = 1$. Curve 2 in Fig. 3 represents the impedance of a filter for a band of substantially the same width, but having only six branches instead of twelve, and with the resistance and selectance the same as for the twelve-branch filter of curve 1, but in which therefore $\Delta S = 2$. Remembering that for the comparatively narrow range of frequencies comprehended within the band there is a roughly approximate correspondence in the variation of the frequency f with α_0 , it will be seen that the curves 1 and 2 show that the device gives a low impedance over the frequency band and a comparatively high impedance at frequencies a little outside the band. Curves 3 and 4 represent the reciprocals of the susceptances, with sign reversed, for the twelve-branch and six-branch filters respectively. These curves are introduced here for the reason that they will be convenient to refer to later on. While these reciprocals of susceptance have the dimensions of reactance, it should be observed that they are not the reactances of the filters.

The greater amplitude of the ripples in curve 2 compared to curve 1 is due to the larger value of the product ΔS , while the greater value of the impedance of the six-branch filter for currents of frequencies within the band is due to the smaller number of parallel paths through which the current may divide in its passage from the generator 11 to the apparatus 12.

The curves 1 and 2 of Fig. 4 are respective-

ly the admittances for the twelve-branch and six-branch filters of Fig. 1. Evidently these curves 1 and 2 of Fig. 4 have as their ordinates the reciprocals of the ordinates of the corresponding curves in Fig. 3. Curves 3 and 4 of Fig. 4 are the susceptances of the twelve-branch and six-branch filter respectively with sign reversed. Curve 1 of Fig. 5 is the conductance of the twelve-branch filter, for which $\Delta S = 1$. Curve 2 of Fig. 5 represents the susceptance of the same twelve-branch filter. Except for the number of branches and the relation $\Delta S = 1$ or $\Delta S = 2$, these curves are quite general in their application, and independent of the particular values assigned for R , S , and ω_0 .

A circuit system designed to present a large impedance to the passage of currents of frequencies within a given band, and only a small impedance for currents outside that band may be constructed of resonant loop circuits as illustrated in Fig. 2. The object of this system is to prevent a band of frequencies from the generator 11 from getting to the apparatus 12 while permitting the passage of currents of frequencies higher or lower than the limits of the band. In other words, the system of resonant loop circuits shown in Fig. 2 is designed to offer a higher impedance to currents of frequency between certain values, but only a low impedance to currents of frequency above or below that range.

The treatment of the problem of Fig. 2 is in close analogy to that of Fig. 1, so that it will presently be made apparent that the solution for Fig. 1 is available with a modified interpretation as a solution for Fig. 2.

Each resonant loop circuit of Fig. 2 is made up of a condenser C , a resistance R , and inductance L in parallel, and these same letters are employed to indicate the measures of the capacity, resistance, and inductance respectively. It is assumed that the resistance of the coil L may be neglected. To avoid confusion with the case of Fig. 1, the various measured quantities of Fig. 2, such as resistances, reactances, etc., will all be indicated by the subscript 1. Accordingly for a sin-

gle resonant loop circuit, such as one of these of Fig. 2, we have the following equations:

$$5 \quad \text{Impedance } z_1 = \frac{1}{\sqrt{G_1^2 + \left(C_1\omega - \frac{1}{L_1\omega}\right)^2}}$$

$$10 \quad \text{Resistance } r_1 = \frac{G_1}{G_1^2 + \left(C_1\omega - \frac{1}{L_1\omega}\right)^2}$$

$$15 \quad \text{Reactance } x_1 = \frac{-\left(C_1\omega - \frac{1}{L_1\omega}\right)}{G_1^2 + \left(C_1\omega - \frac{1}{L_1\omega}\right)^2}$$

$$20 \quad \text{Admittance } y_1 = \frac{1}{\sqrt{G_1^2 + \left(C_1\omega - \frac{1}{L_1\omega}\right)^2}}$$

$$25 \quad \text{Conductance } g_1 = \frac{1}{R_1} = G_1$$

$$30 \quad \text{Susceptance } b_1 = C_1\omega - \frac{1}{L_1\omega}$$

As before, the frequency is f and $\omega = 2\pi f$. Corresponding to the transformation employed in connection with Fig. 1, I find it more convenient to throw these expressions into the form

$$35 \quad z_1 = \frac{1}{G_1} \frac{1}{\sqrt{1 + \alpha_1^2 X_1^2}}$$

$$40 \quad r_1 = \frac{1}{G_1} \frac{1}{1 + \alpha_1^2 X_1^2}$$

$$45 \quad x_1 = \frac{1}{G_1} \frac{-\alpha_1 X_1}{1 + \alpha_1^2 X_1^2}$$

$$50 \quad y_1 = G_1 \sqrt{1 + \alpha_1^2 X_1^2}$$

$$55 \quad g_1 = G_1$$

$$60 \quad b_1 = \alpha_1 G_1 X_1$$

where

$$65 \quad x_1 = \sqrt{\frac{C_1}{L_1 G_1^2}}$$

This function I call the "excludance" of the resonant loop circuit. A comparison of these last expressions for z_1 , r_1 , x_1 , y_1 , g_1 and b_1 for the resonant loop circuits shows that they are the same functions of G_1 , X_1 and α_1 ; that y , g , b , z , r , and x are of R , S , and α_0 respectively for the resonant series branch circuits. Since in the case of the resonant branch circuits of Fig. 1 the conductances and susceptances of the several resonant branches add each to each as scalar quantities, not vectors, while in the case of the resonant loops of Fig. 2 the resistances and reactances of the several loops add each to each as scalar quantities, not vectors, the problem in Fig. 2 is seen to be the exact analogue of that of Fig. 1, provided we substitute the conductance of the loop for the resistance of the resonant

series branch and the excludance of the loop for the selectance of the resonant series branch. Accordingly we may pass over the further steps for the solution of the problem of Fig. 2, and it remains merely to interpret the curves of Figs. 3, 4 and 5 in such a way as to make them applicable to Fig. 2.

Curve 1 of Fig. 3 represents the admittance of the twelve-loop system of Fig. 2. Similarly, curve 2 of Fig. 3 represents the admittance of a six-loop system like Fig. 2. The width of the frequency band is taken substantially the same for the two cases of twelve loops and six loops. Curves 3 and 4 of Fig. 3 are the corresponding reciprocals of the reactances (with their signs reversed) for curves 1 and 2. These quantities have the same dimensions as susceptances, but they are not the susceptances of the system of Fig. 2. Curves 1 and 2 of Fig. 4 are the impedances of the twelve-loop and six-loop embodiments of Fig. 2 respectively, and curves 3 and 4 of Fig. 4 are the corresponding reactances (with their signs reversed). Curves 1 and 2 of Fig. 5 are the resistance and reactance respectively of the twelve-loop system of Fig. 2.

In the case of the resonant branch circuits of the filter of Fig. 1, I expressly neglected the effect of the leakage conductance of each condenser, and in the same way for the resonant loop circuits of Fig. 2, I neglected the effect of the resistance of each coil. The criteria determining when this may be done are as follows:

$$\frac{LG}{CR} \text{ or } \frac{S}{X}$$

is negligible compared to unity for each resonant series branch and

$$\frac{C_1 R_1}{L_1 G_1} \text{ or } \frac{X_1}{S_1}$$

is negligible compared to unity for each resonant loop.

Now that the two special cases have been considered, the general case will be readily apprehended, and it will be understood that the foregoing disclosure has been largely by way of example, and that these systems that I have disclosed need not necessarily be constructed respectively of resonant branches and loops conforming to the above criteria. The general resonant branch circuit is one in which

$$R \left(1 + \frac{S f_0^2}{X f^2} \right)$$

takes the place of R and the general resonant loop circuit is one in which

$$G_1 \left(1 + \frac{X_1 f_1^2}{S_1 f^2} \right)$$

takes the place of G in the more restricted

cases we have considered. If we call these two functions the effective resistance R' and effective leakage conductance G_1' respectively, then the rules given above for the construction of the systems of Fig. 1 and Fig. 2 apply provided the effective resistance and effective conductance be substituted for the resistance and conductance of the resonant branch and loop circuits respectively. In practice, the width of the frequency band in any case will be small compared to the medial frequency of the band, and although it is true that effective resistance and conductance are functions of frequency, the variation with frequency will be so little within the band that the substitution above suggested will be entirely practicable. In the practical case, where the width of the frequency band is small compared to the medial frequency, the factor

$$\frac{f_n^2}{f^2}$$

will be substantially unity for all frequencies within the band, and accordingly we may write

$$R' = R \left(1 + \frac{S}{X} \right)$$

for the effective resistance of the series branches, and likewise we may write

$$G_1' = G_1 \left(1 + \frac{X_1}{S_1} \right)$$

for the effective conductance of the loops. Accordingly, the general selectance becomes

$$S' = \sqrt{\frac{L}{CR^2}}$$

and the general excladance becomes

$$x' = \sqrt{\frac{C_1}{L_1 G_1^2}}$$

When it becomes desirable to employ these impedance networks in radio circuits to present an extreme impedance over a certain frequency band, and an oppositely extreme impedance outside that band, a difficulty is encountered because whether open aerials or closed aerials are used and whether for transmitting or receiving, they have a pronounced inherent reactance of their own which must be neutralized throughout the band if the impedance of the circuit is to be maintained approximately constant throughout the band. Also when such networks are used in local circuits associated with transmitting and receiving conductors, either in radio transmission or high frequency wire transmission, these local circuits may have inherent reactances which should be neutralized throughout the band.

Such a neutralization may under many

circumstances be accomplished by specially proportioning the constants of the elemental resonant branches or loops of the network. This may be a somewhat complicated manner of design presenting a more or less different problem in each case. Another way of dealing with such a situation is to use a separate device for neutralizing the natural or inherent reactance over the desired frequency band.

Among the more important cases for which it will be desired to neutralize the reactance, the latter will have one of three forms $L\omega$, $-\frac{1}{C\omega}$ and $\alpha_o RS$. The first two forms may always be reduced to the third form. When the reactance is a pure inductance reactance, the addition of a capacity reactance in series will produce the third form, while if the reactance be a pure capacity reactance, the addition of an inductance reactance in series will produce the third form. The third form is, as will be readily appreciated from the earlier part of this specification, that of a resonant circuit having the periodicity ω_0 .

Having reduced the reactance of the circuit to the form $\alpha_o RS$, we then put in additional reactance so chosen as to make the α_o of the resulting resonant circuit correspond to the medial frequency of the band of frequencies over which the reactance is to be neutralized; we may then add a series of loop circuits which will completely neutralize this reactance $\alpha_o RS$ over a band of frequencies corresponding to values of α_o from $-\Delta$ to $+\Delta$.

For this purpose we may use one or more loop resonant circuits connected in series as illustrated in Fig. 2. When the band is narrow and a high resistance is not objectionable, a single loop circuit may be adequate; but when the band is wide and a high resistance is to be avoided, a plurality of these circuits as explained for Fig. 2 should be employed.

The theory of operation of these band reactance neutralizers involves the following considerations: The reactance of a resonant circuit, in which G is sufficiently small, is $\alpha_o RS$, and the reactance of a loop circuit attuned to the same periodicity, and in which R is sufficiently small, is

$$-\frac{\alpha_o X_1}{G_1(1 + \alpha_o^2 X_1^2)}$$

In this expression, when $\alpha_o^2 X_1^2$ is negligibly small compared to unity, the expression reduces to

$$-\frac{\alpha_o X_1}{G_1}$$

and this reactance will exactly neutralize

the reactance of the series resonant circuit when

$$5 \quad RS = \frac{X_1}{G_1}$$

For the purpose of a concrete illustration, let us assume that 0.04 is the largest quantity which we can regard as negligible in comparison with unity. Accordingly $\alpha_0^2 X_1^2 = 0.04$ represents the limiting value of $\alpha_0^2 X_1^2$ in a single loop neutralizer, so that in this case we have $\Delta X_1 = 0.2$. Therefore in the case of the single loop neutralizer we have these conditions:

$$10 \quad \Delta X_1 = 0.2 \text{ and } RS = \frac{X_1}{G_1}$$

20 latter equation reducing to

$$\sqrt{\frac{L}{C}} = \frac{1}{G_1} \sqrt{\frac{C_1}{L_1}}$$

25 where

$$X_1 = \sqrt{\frac{C_1}{L_1 G_1^2}}$$

30 and where C_1 , L_1 , and G_1 are the capacity, inductance, and conductance respectively of the loop. The resistance of this loop throughout the band of width 2Δ will be substantially $\frac{1}{G_1}$. This single loop band reactance neutralizer is illustrated in Fig. 6, and characteristic curves for it are shown in Fig. 7, where curve 1 is the reactance $\alpha_0 RS$ of the resonant circuit to be neutralized, curve 2 is the reactance of the neutralizing loop circuit, and curve 3 is the resultant reactance of the entire circuit comprising the reactance neutralizer. When more than one loop circuit is to be used as indicated in Fig. 8, the width of the band is not restricted to those values of $\alpha_0^2 X^2$ of the elemental loops which are negligible compared to unity, but the band width may advantageously be broadened to comprehend all values of $\alpha_0 X$ of the elemental loops to $\alpha_0 X = 1$. This is illustrated in Fig. 9 which shows characteristic curves for the network of Fig. 8.

35 In the three-loop band reactance neutralizer of Fig. 8, the respective loops are tuned to periodicities such that $\alpha_0 = -\Delta \alpha_0 = 0$, and $\alpha_0 = \Delta$ respectively. It will be understood that in Fig. 9 all the ordinates are reactances and the abscissæ are values of the frequency function α_0 . Curve 1 is the reactance $\alpha_0 RS$ of the given resonant circuit to be neutralized. Curves 2, 3, and 4 are the reactances of the three elemental loops respectively, curve 5 is the sum of curves 2, 3 and 4, and curve 6 is the resultant reactance of the entire circuit as modified by the reactance neutralizer.

Any number of loop circuits may be used in a band reactance neutralizer, and the effect of increasing the number of loops is to increase the width of the band or to diminish the resistance, or both.

10 It is believed that the foregoing discussion of a few examples of the use of band reactance neutralizer will sufficiently indicate their utility in various connections. To carry the particular examples already discussed a little further; that is, to make them still more specific, the filament and grid of an audion have been indicated in Figs. 6 and 8. The most effective condition is that in which the conductance of this translating device is made the conductance of a band reactance neutralizer which neutralizes the reactance $\alpha_0 RS$, of the resonant circuit with which the translating device is connected. This mode of connection is the most efficient possible. The magnitudes of the reactance of a loop is not affected by the algebraic sign of the conductance G_1 , so that the translating device may have a negative conductance in which case it becomes regenerative.

20 By means of the general method which I have illustrated in the foregoing specification, it will be seen that it is possible to design a circuit such that between $\alpha = +\Delta$ and $\alpha = -\Delta$ laid off on a scale of abscissæ, this circuit shall have a circuit function such as reactance, admittance, etc., corresponding to any given finite single valued, odd or even function of α between those limits, the circuit function being odd or even, according as it is resistance, conductance, impedance or admittance on the one hand or reactance or susceptance on the other hand.

25 What I claim is:

30 1. A circuit comprising a source of electro-motive force, a device to which currents are to be applied as generated from said source, and an interposed network, said network comprising a plurality of similar combinations, each combination consisting of two terminals with a resistance, a capacity and an inductance connected alike between said two terminals, the resistances in the several combinations being equal, all the combinations being connected alike in respect to the said circuit, the combinations all having the same selectance of value not greater than unity and having their frequency functions in arithmetical progression with a relatively small common difference, whereby the network has a substantially uniform impedance over the frequency range corresponding to the said frequency functions and has a widely different impedance outside that frequency range.

35 2. A circuit comprising a source of electromotive force, a device to which currents are to be applied as generated from said source, and an interposed network, said network comprising a plurality of similar com-

binations, each combination consisting of two terminals and a resistance, a capacity and an inductance connected alike between said two terminals, all the combinations being connected alike in said circuit and all having the same selectance and having their frequency functions in arithmetical progression with a relatively small common difference, whereby the network offers a substantially uniform impedance to currents of the frequency range corresponding to said frequency functions and a widely different impedance to currents of frequencies outside that range.

15. 3. A circuit comprising a source of electromotive force, a device to which currents are to be applied as generated from said source, and an interposed network, said network comprising a plurality of similar combinations, each combination consisting of two terminals and a resistance, a capacity and an inductance connected alike between said two terminals, all the combinations being connected alike in said circuit, the combinations having their frequency functions in arithmetical progression with a relatively small common difference and each having its resistance, capacity and inductance proportioned to make the impedance-frequency characteristic of the network of substantially uniform slope over the frequency range corresponding to said frequency functions with a widely different value for the impedance at frequencies outside that range.

35. 4. A circuit comprising a source of electromotive force, a device to which currents are to be applied as generated from said source, and an interposed network, said network comprising a plurality of similar combinations, each combination consisting of two terminals and a resistance, a capacity and an inductance connected alike between said two terminals, the resistances in the several combinations being equal, all the combinations being connected alike in said circuit, and the combinations all having the same selectance.

50. 5. A circuit comprising a source of electromotive force, a device to which currents are to be applied as generated from said source, and an interposed network, said network comprising a plurality of series loops, each loop consisting of a resistance, a capacity and an inductance in parallel, the resistances in the several loops being equal,

all the loops being connected alike in said circuit, the loops all having the same selectance and having their anti-resonant frequencies approximately in arithmetical progression with a small common difference. 60

6. A circuit comprising a source of electromotive force, a device to which currents are to be applied as generated from said source, and an interposed network, said network comprising a plurality of series loops, 65 each loop consisting of a resistance, a capacity and an inductance in parallel, the loops having their frequency functions approximately in arithmetical progression with a relatively small common difference and 70 each loop having its resistance, capacity and inductance proportioned so that the impedance-frequency characteristic of the network shall have a substantially continuous predetermined form. 75

7. A network comprising a plurality of loops connected in series, each loop consisting of a resistance, a capacity and an inductance in parallel, the resistances being equal, the loops all having the same selectance and 80 having their anti-resonant frequencies in arithmetical progression with a relatively small common difference, whereby the network has a low and substantially uniform impedance for all frequencies within the 85 range of said arithmetical progression and a high impedance for frequencies outside that range.

8. A circuit comprising a source of electromotive force, a device to which currents 90 are to be applied as generated from said source, and an interposed network, said network comprising a plurality of similar combinations, each combination consisting of two terminals and a resistance, a capacity 95 and an inductance connected alike between said two terminals, all the combinations being connected alike in said circuit and all having the same selectance and having their frequency functions in arithmetical progression with a relatively small common difference, the combinations corresponding to consecutive terms of the arithmetical progression having their resistances of nearly the same value. 100

In testimony whereof, I have signed my name to this specification this 18th day of November, 1920.

JOHN STONE STONE.
